UNITED STATES PATENT OFFICE.

WILLIAM I. GRUBB, OF POTTS TOWN, PENNSYLVANIA.

DESIGN FOR A CRANK-HANGER FOR BICYCLES.

SPECIFICATION forming part of Design No. 27,578, dated August 24, 1897.

Application filed May 29, 1897. Serial No. 638,817. Term of patent 7 years.

To all whom it may concern:

Be it known that I, WILLIAM I. GRUBB, a citizen of the United States, residing at Pottstown, in the county of Montgomery and State 5 of Pennsylvania, have invented and produced a new and original Design for Crank-Hangers; and I do hereby declare the following to be a full, clear, and exact description of the same, reference being had to the accompanying 10 drawings, forming a part thereof.

This is a design for a crank-hanger for bicycles.

In the accompanying drawings, Figure 1 is a view in side elevation. Fig. 2 is a top plan 15 view.

Referring to the drawings, A designates a cylindrical or barrel portion formed in a frame B, which comprises a vertical tube or member b and a forwardly-extended inclined tube

or member b', both extending from barrel A. 20 At the upper end of tube or member b is tube or member b², which is formed with a decided depending curve, making the same of approximately U shape in side elevation, the same being joined to member b' by a short tube b³. 25 From the rear of the cylindrical or barrel portion A extend two parallel tubes b⁴, united by a brace C.

I claim as my invention—

The design for a crank-hanger for bicycles, 30 substantially as shown and described.

In testimony whereof I affix my signature in presence of two witnesses.

WILLIAM I. GRUBB.

Witnesses:

LOUIS ALLGAIER,
ED. A. KELLY.
